CLAIM

The ornamental design for a flying toy, as shown and described.

DESCRIPTION

FIG. 1 is a perspective view of the flying toy showing the new design;

FIG. 2 is a top plan view of the flying toy shown in FIG. 1; FIG. 3 is a bottom plan view of the flying toy shown in FIG. 1; and,

FIG. 4 is a side view of the flying toy shown in FIG. 1. The portions shown in broken lines are for illustrative purposes only; and form no part of the claimed design.
